UNITED STATES PATENT OFFICE.

WILLIAM H. MARGERISON AND ALBERT E. MARGERISON, OF PHILADELPHIA, PENNSYLVANIA.

DESIGN FOR A TERRY TOWEL.

56,824.

Specification for Design.

Patented Dec. 28, 1920.

Application filed May 9, 1919. Serial No. 296,004. Term of patent 14 years.

To all whom it may concern:

Be it known that we, WILLIAM H. MARGERISON and ALBERT E. MARGERISON, citizens of the United States, both residing at Philadelphia, in the county of Philadelphia and State of Pennsylvania, have invented a new, original, and ornamental Design for Terry Towels, of which the following is a specification, reference being had to the accompanying drawings, forming a part thereof, in which—

one face of a terry towel showing our new design, and

Fig. 2 is a perspective view showing the opposite face of the towel shown in Fig. 1.

We claim:

The ornamental design for a terry towel, as shown.

WILLIAM H. MARGERISON.
ALBERT E. MARGERISON.
